UNITED STATES PATENT OFFICE.

RUDOLF RICKENBACHER, OF PATERSON, NEW JERSEY.

TAKE-UP MECHANISM FOR LOOMS.

SPECIFICATION forming part of Letters Patent No. 408,262, dated August 6, 1889.

Application filed June 1, 1888. Serial No. 275,701. (No model.)

To all whom it may concern:

Be it known that I, RUDOLF RICKENBACHER, a citizen of the United States, residing at Paterson, Passaic county, State of New Jersey, have invented a new and useful Improvement in Take-Up Mechanism for Looms, of which the following is a specification, reference being had to the accompanying drawings, forming a part thereof.

10 My invention relates to take-up mechanism for looms, and has for its object to so actuate the cloth-beam as to cause the beam to take up the cloth at a uniform rate of speed during the various stages of its enlargement, owing to the winding of the cloth thereon.

The invention consists in devices and combinations of devices, which will be hereinafter fully described, and pointed out in the claim.

Figure 1 of the drawings shows in elevation one end of an ordinary loom with my invention attached. Fig. 2 is an enlarged view of the take-up mechanism detached. Fig. 3 is a part front view of the same. Fig. 4 shows a portion of the regulating mechanism, and 25 Fig. 5 is a part sectional plan of the device on line $x x$ of Fig. 2.

A represents one end of an ordinary loom, having the usual frame A', lay b, cloth-beam C, heddles d, crank-shaft e, pitman f, warp-reel g', driving-gears h and i, and balance-wheel k. The loom, being constructed as is usual, needs not, it is thought, to be further described herein.

To the frame A', and in a suitable position 35 thereon, I fix by bolts or otherwise a plate or bar B, in the upper end of which bar I arrange one end of the shaft of the cloth-beam C, and fix on the said end of said shaft a gear-wheel C', on which gear I place pins C² and C³. The gear C' gears with and is actuated by a pinion D, that is integral with a gear-wheel E, meshing with and receiving its motion from a pinion F, integral with a gear-wheel G', which latter is turned by a pinion H, that is integral with a ratchet-wheel L, all 40 of the said gears and pinions being arranged on studs fixed in the bar B, and as shown. On the stud m of the ratchet-wheel L, I pivot loosely a slotted lever N, and mount an additional ratchet-wheel O, which latter has integral with it a bevel-gear P, that gears with and actuates a like bevel-gear P', fixed on the

inner end of a screw R, which latter is arranged in a bearing formed in the lever N, and which is provided with an eye-nut R', as 55 shown. The lever N is provided with pawls S S and plate B, with pawls S' S', to act upon the wheel L, as hereinafter stated.

In a slot formed in a plate T², projecting from bar B, I arrange the lower end of a movable bar T, which bar is provided with a round screw-threaded upper end, and has pins 1 and 2 secured therein, and a spring Z, surrounding said end, and carries pawls T', said bar also passing through an eye-stud T⁴, fixed in 60 a projecting lug T⁵, fastened to plate or bar B, the spring Z being placed between pin 2 and said stud T⁴. On the upper screw-threaded portion of the bar T, I fix by jam-nuts a depending bracket W, and arrange in said 70 bracket a screw J', that carries a nut J⁹, having a pin J, and a bevel-gear J², which latter gears with a like gear J³, integral with a ratchet-wheel J⁴, arranged on a stud J⁵, fixed in the bracket W.

The loom is supposed to be in motion. The lay b, actuated by the driving mechanism shown, by means of cord f², passing around pulley f', imparts an up-and-down movement to the lever N, which lever in each upward 80 movement of the same causes the pawls S S to engage the teeth of the wheel L and turn the same, the pawls S' S' serving as retaining-pawls, and in this way impart intermittent movement to the ratchet-wheel L and a 85 like movement to the cloth-beam C by means of the train of wheels described between the ratchet-wheel and cloth-beam. The take-up mechanism having been adjusted by the weaver as the weaving proceeds, and a certain 90 number of yards having been woven and the fabric wound on the beam and the tension on the cloth increased by such enlargement of the beam C, the pin C² engages pin J, which forces the bar T downward, which action of 95 the bar compresses spring Z, causes pawls T' T' to turn ratchet-wheel O and gear P, which latter turns screw R and carries nut R' outward on the said screw R, which shortens the stroke of the lever N, (the cord f² being attached to said nut,) causing the pawls S' S' to take up a less number of teeth on the wheel L at each upward movement of the lever N 100 and decreasing the speed of the cloth-beam C.

The pin J having escaped from the pin C² and the bar T having been raised to the position shown by the action of the spring Z, the pin C³ next engages the ratchet-wheel J⁴ in the 5 rotation of wheel C', and in its engagement therewith turns wheel J⁴, which by means of gears J² J³ turns the screw J' and raises the pin J on the said screw J' preparatory to a further depression of the bar T, a further outward movement of the nut R' on the screw R, a further shortening of the stroke of the 10 lever N, and a further decrease in the speed of the cloth-beam C, the action being repeated at each succeeding revolution of the wheel C' and engagement of the pins C² and C³, respectively, with the pin J and ratchet-wheel J⁴.

Having described my invention, I claim as new and desire to secure by Letters Patent—
The combination, with the cloth-beam and

the gear C' thereon, ratchet L, the gearing intermediate said ratchet and the gear C', the lever N, a pawl or pawls thereon, and means for vibrating said lever, of screw R, nut R', to which said vibrating means are connected, the bevel-gear on said screw, the bevel-gear 20 P, the ratchet O, to which gear P is connected, the bar T, pawls carried thereby and engaging said ratchet O, the frame B, the spring Z, the bracket carried by said bar T, the screw-threaded rod mounted in said bracket, the 25 bevel-gears J² J³, the ratchet J⁴, the pins C² C³, and the nut J⁹, carrying pin J, all arranged and operating substantially as described.

RUDOLF RICKENBACHER.
